(57) **ABSTRACT**

The sock pairing system includes a loop that is attached adjacent the top edge of socks and is used to attach pairs of socks to keep a plurality of socks sorted during laundering. The effective length of the loop is the length of the loop between the ends of the loop that are attached to the sock. The effective length of the loop is selected based on the type of sock to which the sock pairing system is attached. The sock pairing system may also include an optional pocket. In its extended position the loop extends out of the pocket, and in its tucked position the loop is tucked into the pocket. The pockets may also be color-coded, such that pairs of socks can be readily identified from a plurality of socks, should the socks become separated prior to or during laundering.

SOCK PAIRING SYSTEM

CROSS-REFERENCE TO RELATED APPLICATION

This application claims the benefit of U.S. Provisional Patent Application No. 63/153,738, filed on Feb. 25, 2021.

BACKGROUND

1. Field

The disclosure of the present patent application relates generally to footwear, such as socks and hose, and particularly to a sock pairing system.

2. Description of the Related Art

Some sock pairing systems may include a loop or open pocket/elastic member, as shown and described in my prior U.S. Patent Publication No. US 2004/0123377, published Jul. 1, 2004. Examples of such sock pairing systems are shown in FIGS. 6-8, below. In FIG. 6, the sock pairing system includes inner loops IL having their ends LE attached and extending from the inner surface of cuffs C of both the left A and right B sock of a pair of socks. In FIG. 7, the sock pairing system includes outer loops OL having their ends LE attached and extending from the outer surface of cuffs C of both the left A and right B sock of a pair of socks. FIG. 8 shows a sock pairing system that connects the two socks A, B, by inserting one sock (in this example, the right sock B) into the loop IL of the other sock (in this example, the left sock A). While such sock pairing systems are useful for keeping a pair of socks together during washing and drying of the socks, they may be improved upon. Such sock pairing systems do not take into consideration the size of the socks. For larger socks, it may be difficult to insert one sock into the loop of the other. For smaller socks, the loops may not be small enough to keep the socks together during rigorous wash cycles. In addition, the outer loops OL are visible and therefore present poor aesthetics when the cuff C of the socks A, B are visible. The inner loops IL are not visible when tucked into the sock, but may be uncomfortable, as they scrape against the skin of the wearer. Thus, a sock pairing system solving the aforementioned problems is desired.

SUMMARY

The sock pairing system includes a loop that is attached adjacent the top edge of each sock in a pair of socks and is used to attach the pair of socks to keep the socks sorted during laundering. The effective length of each loop is the length of the loop between the ends of the loop that are attached to the sock. The loops may be circular (cords) or rectangular (strips) in cross-section and may be in the form of nylon elastic strings to provide strength and comfort should the strings contact the skin of the wearer. The effective length of the loop is selected based on the type of sock to which the sock pairing system is attached. The type of sock may include such attributes as the thickness of the material of the sock, the height of the sock, the size of sock, and other attributes that can affect the ability to pass a single sock through a loop attached to the other sock of the pair. The sock pairing system may also include an optional pocket. In an extended position, the loop extends out of the pocket in order to be looped around the other sock of a pair

2

of socks. In a tucked position, the loop is tucked into the pocket to hide the loop from view or to protect the skin of the wearer. The pockets may be made of elastic nylon and may be dimensioned and configured according to the type of sock to which they are attached. The pockets may also be color-coded, such that one pair of socks can be readily identified in a pile of socks, should the socks become separated prior to or during laundering. The colors may also be used to identify the owner or wearer of the sock, when the socks of several individuals are laundered together.

These and other features of the present subject matter will become readily apparent upon further review of the following specification and drawings.

15 BRIEF DESCRIPTION OF THE DRAWINGS

FIG. 1 is a perspective view of a pair of socks in a sock pairing system having loops and a pocket attached to an inner surface of the cuff of each of the socks.

20 FIG. 2 is a perspective view of a pair of socks in a sock pairing system having loops and a pocket attached to an outer surface of the cuff of each of the socks.

FIG. 3 is a perspective view of the pair of socks of FIG. 1, showing the socks connected using the sock pairing system.

25 FIG. 4 is an enlarged partial perspective view of the sock pairing system of FIG. 2, showing a loop of the sock pairing system extending out of a pocket of the sock pairing system.

FIG. 5 is an enlarged partial perspective view of the sock 30 pairing system of FIG. 2, showing the loop of the sock pairing system tucked into the pocket of the sock pairing system.

FIG. 6 is a perspective view of a pair of socks of an 35 exemplary sock pairing system of the prior art having a loop extending from an inner surface of a cuff of the socks.

FIG. 7 is a perspective view of a pair of socks of an exemplary sock pairing system of the prior art having loops extending from an outer surface of a cuff of the socks.

40 FIG. 8 is a perspective view of the pair of socks of FIG. 6, showing the socks connected using the prior art sock pairing system.

FIG. 9 is a chart showing different size socks that can be equipped with the sock pairing system of FIGS. 1 and 2.

45 Similar reference characters denote corresponding features consistently throughout the attached drawings.

DETAILED DESCRIPTION OF THE PREFERRED EMBODIMENTS

The sock pairing system 100 is shown in FIGS. 1-5. In FIG. 1, the sock pairing system 100 is attached to the inside of the cuffs C of a pair of socks, including a left sock A and a right sock B. It should be understood that as with most socks, the left sock A and the right sock B are identical to one another and the terms left and right are used simply to represent a pair of socks A, B. It should also be understood that the sock pairing system 100 can be used with socks not having cuffs, in which case the sock pairing system 100 is attached to the body of the sock, adjacent its top edge. In FIG. 2, the sock pairing system 100 is attached to the outside of the cuffs C of the socks A, B. As is shown in FIG. 3, to attach the socks to one another for laundering purposes, one of the socks B is guided through the loop 102 of the other sock A. The effective length of the loop 102 is the length of the loop 102 between the stitch line(s) 400 that attach the ends 402 of the loop 102 to the sock S, as shown in FIG. 4. It should be noted that while the loops 102 are shown as

circular or round in cross section, other cross sectional shapes, such as rectangular (strips) or flat, could be used. In one embodiment, the loops **102** are nylon elastic strings with circular cross sections 3 mm in diameter, to provide strength and comfort should the strings contact the skin of the wearer.

FIG. 9 shows a number of different sock types that can incorporate the sock pairing system **100**. If the effective length of the loop **102** of the sock pairing system **100** is too short for the larger sock types, it can be difficult to guide one sock into the loop **102** of the other. If the effective length of the loop **102** of the sock pairing system **100** is too long for the smaller sock types, the socks may become separated during the laundering process. To avoid this issue, the effective length of the loop **102** of the sock pairing system **100** is selected based on the type of sock to which the sock pairing system **100** is attached. The type of sock can include such attributes as the thickness of the material of the sock, the height of the sock, the size of sock, and other attributes that can affect the ability to pass the sock through a loop. For example, for the "liner" sock, an effective length for the loops is 2.6 cm, and a loop (strip) width of 0.635 cm. An example of a larger size sock is the "crew" sock, wherein an effective length for the loops is 3.5-4.0 cm, and a loop (strip) width of 0.635 cm. These are only examples, and it should be understood that the effective lengths, cross sections and widths of the loops **102** can be determined through experimentation.

The details of the sock pairing system **100** are shown in FIGS. 4-5. The sock pairing system **100** includes an optional pocket **104**. The pocket **104** is formed by stitching **400** that attaches the two side edges and the bottom edge of the pocket **104** to the cuff C (or the top of a sock without a cuff). The ends **402** of the loop **102** can be anchored to the pocket **104** and the sock by the bottom seam of stitching **400**. As shown in FIG. 1, the loops **102** and the pockets **104** may be sewn to the inside of the cuff C, or inside tops of the socks A, B. Alternatively, as shown in FIG. 2, the loops **102** and the pockets **104** may be sewn to the outside of the cuff C, or outside tops of the socks A, B. In FIG. 4, the loop **102** is shown in its extended position, extending out of the pocket **400**. In this position, the loop **102** is in position to be looped around the other sock of the pair of socks A, B. In FIG. 5, the loop **102** is shown in its tucked position, tucked into the pocket **104**. In this position, the loop **102** is hidden from view in the external embodiment as shown in FIG. 2, thereby providing a more aesthetic appearance. In the internal embodiment as shown in FIG. 1, the pocket **104** is between the loop **102** and the wearer's skin, thereby protecting the skin from possible irritation. In one embodiment, the pockets **104** may be made of elastic nylon, similar to the loops **102**. As with the loops **102**, the pockets **104** may be sized

according to the type of sock to which they are attached. The pockets **104** may also be color-coded, such that pairs of socks can be readily identified from a plurality of socks, should the socks become separated prior to or during laundering. The colors may also be used to identify the owner or wearer of the sock, when the socks of several individuals are laundered together.

It is to be understood that the sock pairing system is not limited to the specific embodiments described above but encompasses any and all embodiments within the scope of the generic language of the following claims enabled by the embodiments described herein, or otherwise shown in the drawings or described above in terms sufficient to enable one of ordinary skill in the art to make and use the claimed subject matter.

I claim:

1. A sock pairing system for attachment to a sock, the sock pairing system comprising a loop having two ends adapted for attachment to the sock and an effective length between the loop's two ends, the sock having a type, the effective length of the loop being dependent on the sock type;

wherein the sock pairing system further comprises the sock, wherein:

the sock is made of a material having a thickness and has a height and a size; and
the type of sock is related to the thickness of the material of the sock, the height of the sock, and the size of sock; wherein the sock pairing system further comprises a pocket, wherein:

the loop may be in an extended position in which the loop extends out of the pocket;

the loop may be in a tucked position in which the loop is tucked inside the pocket,

the pocket includes two side edges and a bottom edge; and the pocket is attached to the sock by stitching that extends along and attaches the two side edges and the bottom edge of the pocket to the sock; and
wherein the stitching extending along the bottom edge of the pocket also attaches the two ends of the loop to the sock.

2. The sock pairing system as recited in claim 1, wherein the pocket is color-coded to identify pairs of socks from a plurality of socks.

3. The sock pairing system as recited in claim 1, wherein the pocket is color-coded to identify types of socks from a plurality of socks.

4. The sock pairing system as recited in claim 1, wherein the pocket is color-coded to identify socks belonging to a particular wearer from a plurality of socks.
